UNITED STATES PATENT OFFICE.

STUART BROADWELL AND CLARENCE HOLLOWAY, OF SPRINGFIELD, ILLINOIS.

CAPSULE-FILLER.

1,144,634.

Specification of Letters Patent. Patented June 29, 1915.

Application filed March 14, 1914. Serial No. 824,762.

To all whom it may concern:

Be it known that we, STUART BROADWELL and CLARENCE HOLLOWAY, citizens of the United States, residing at Springfield, in the county of Sangamon and State of Illinois, have invented new and useful Improvements in Capsule-Fillers, of which the following is a specification.

Our invention relates to improvements in capsule fillers.

The primary object of our invention is to provide a simple appliance for use in the filling of capsules, in which means will be provided for the speedy and accurate measuring of the powder, or like ingredient, without the use of cumbersome devices, and which will be sanitary and efficient, and yet inexpensive of manufacture.

To accomplish the foregoing objects and to secure other and further advantages in the matter of construction, arrangement, and use, our invention involves certain new and useful details of design and construction as will be hereinafter fully described and then pointed out specifically in the appended claims.

In the accompanying drawings, forming part of this specification, Figure 1 is a perspective view of a capsule filler embodying our invention. Fig. 2 is a longitudinal vertical sectional view through our capsule filler. Fig. 3 is a sectional view of our capsule filler, taken on line 2-2 of Fig. 2.

In all figures, like characters of reference wherever they occur indicate corresponding parts.

The capsule filler of our invention may be cast of brass, or the like, or may be formed of glass, or other non-porous material, and is preferably formed in a single piece. Numeral 1 designates the tray portion, supported for convenience by supporting flanges designated as 2. Tray 1 is provided with a series of parallel lateral grooves 3, semi-circular in cross-section, and of equal depth and width, which grooves are of constantly decreasing depth adjacent each end, the bottom of the grooves rounding upward at each edge of the tray. (See Fig. 3.) Grooves 3 are formed of a predetermined capacity, that is, of a size to hold an approximately known quantity of powder when

filled to the level of the top of the tray. The capsule body may then be inserted, open end inward, at one end of the groove, and the capsule top, also open end inward, at the opposite end of the groove, and the two brought together along the groove. It will be readily seen that the powder lying in the groove will be taken up by the two capsule elements as they are brought together, and that a negligible portion of the powder will escape.

We prefer to provide our device with a longitudinally extending flange 5 on one side of the tray, upon which the consecutive numbers of the grooves may be indicated. Thus the operator may readily see the exact number of capsules that have been filled, or divide the powder evenly among a given number of capsules with absolute accuracy, it being only necessary to use a straight-edged tool of any kind to smooth off the powder in the grooves which are filled above the level of the tray.

From the foregoing description, it will be readily seen that our invention provides an inexpensive and simple device wherein capsules may be filled readily and speedily, and in which accurate means are provided for proportioning the material for the capsules and measuring it with considerable accuracy.

While we have described and shown the preferred embodiment of our invention, we do not wish to be limited strictly thereto, except for such limitations as the claims may import.

Having thus described our invention, what we claim is:

1. A tray for use in filling capsules, comprising grooves semi-circular in cross-section, and said grooves being formed with constantly decreasing depth at each extremity.

2. A tray for use in filling capsules, comprising a plurality of grooves semi-circular in cross-section adapted to receive material to be inserted in capsules, said grooves being formed with constantly decreasing depth at each extremity and each of said grooves providing a slide-way whereby the open ends of a capsule may be brought together along said groove and the material con-

tained in said groove inserted in the capsule.

3. A tray for use in filling capsules, comprising a plurality of identical parallel 5 grooves semi-circular in cross-section and of a predetermined volume adapted to receive material to be inserted in capsules, and said

grooves being formed with constantly decreasing depth at each extremity.

STUART BROADWELL.
CLARENCE HOLLOWAY.
